UNITED STATES PATENT OFFICE

JOSEPH A. MAHONEY, OF BROOKLYN, AND ARTHUR ZITZMANN, OF OZONE PARK, NEW YORK, ASSIGNORS TO BELL TELEPHONE LABORATORIES, INCORPORATED, OF NEW YORK, N. Y., A CORPORATION OF NEW YORK

DESIGN FOR A COMBINED TABLE AND COVER FOR TELEGRAPH PRINTER

Application filed December 20, 1930. Serial No. 38,053. Term of patent 14 years.

To all whom it may concern:

Be it known that we, JOSEPH A. MAHONEY and ARTHUR ZITZMANN, citizens of the United States, residing at Brooklyn, in the county of Kings and State of New York, and at Ozone Park, in the county of Queens and State of New York, respectively, have invented a new, original, and ornamental Design for Combined Table and Cover for Telegraph Printer, of which the following is a specification, reference being had to the accompanying drawing, forming part thereof.

Fig. 1 of the drawing is a perspective view of the printer table with the cover in place showing our new design;

Fig. 2 is a plan view of the printer cover alone; and

Fig. 3 is a side view of the combined printer table and cover.

We claim:

The ornamental design for a combined telegraph printer cover and printer table as shown.

In witness whereof, we hereunto subscribe our names this 18th day of December, 1930.

JOSEPH A. MAHONEY.
ARTHUR ZITZMANN.
